GRINDING APPARATUS

Clarence J. Green, Worcester, Mass., assignor to
 Norton Company, Worcester, Mass., a corpora-
 tion of Massachusetts

Application February 6, 1936, Serial No. 62,661

8 Claims. (Cl. 51—101)

This invention relates to grinding machines, and more particularly to an apparatus for grinding a work piece of non-circular cross section.

It is an object of this invention to provide a simple and thoroughly practical grinding apparatus for grinding a work piece to a non-circular shape. It is another object of this invention to provide such a grinding apparatus which is simple, rugged and compact in construction and simple in operation and use.

It is a further object of this invention to provide a grinding apparatus for grinding a work piece of non-circular cross section in which the work piece is oscillated toward and from the grinding wheel by means of a rotatable cam. A further object of this invention is to provide a grinding apparatus of this type with a cam for oscillating the work piece which is adjustable so as to permit varying the shape of the work piece being produced.

It is a further object of this invention to provide a piston grinding attachment for grinding an oval or elliptical surface on the periphery of a work piece, such as a piston. It is a further object of this invention to provide a piston grinding attachment which is portable in structure and may be readily mounted on a standard cylindrical grinding machine. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing, in which is shown one of various possible embodiments of the mechanical features of this invention,

Fig. 1 is a fragmentary front elevation of a grinding machine showing the improved grinding attachment in operative position thereon;

Fig. 2 is a longitudinal vertical section through the grinding attachment;

Fig. 3 is a cross sectional view, taken approximately on the line 3—3 of Fig. 2;

Fig. 4 is a fragmentary sectional view, showing a modification of the arrangement shown in Fig. 3; and

Fig. 5 is a fragmentary plan view of the attachment, as shown in Fig. 2.

A cylindrical grinding machine has been illustrated in the drawing, comprising a base 10 which supports a longitudinally reciprocable work table 11 on the usual flat and V-ways (not

shown). The longitudinally reciprocable table 11 is provided with a rotatable work support comprising a motor driven headstock 16 and a footstock 17 which serve to support the grinding attachment 18 in operative position on the machine.

A rotatable grinding wheel 20 is supported on a rotatable wheel spindle (not shown) which is in turn supported on a wheel slide 22. The wheel slide 22 is arranged to slide transversely on the base 10 on a pair of spaced slideways (not shown). The wheel slide 22 is arranged to be moved transversely relative to the base 10 by means of a suitable wheel feeding mechanism. This mechanism may be of any well known type, such as for example that shown in the prior United States Patent to Norton No. 762,838 dated June 14, 1904. This mechanism has not been shown in detail in the present case, since it is not considered part of the present invention. For details of disclosure, reference may be had to the above-mentioned patent. A rotatable hand wheel 25 is mounted on the front of the machine base and is operatively connected to rotate a feed screw (not shown) to cause the wheel 20 and wheel slide 22 to be moved transversely toward or from the work supporting table 11, depending on the direction of rotation of the feed wheel 25.

In the construction illustrated in the drawing, the work supporting table is arranged to be reciprocated longitudinally relative to the base 10 and the grinding wheel 20 to traverse a work piece to be ground past the operative face of the grinding wheel 20. The table 11 is provided with a depending rack bar 30 by which the table may be traversed by a manual or power traverse mechanism, such as that shown in the prior patent above referred to. This mechanism has not been shown in detail, since it is not considered part of the present invention. Reference may be had to the above-mentioned expired patent for details of disclosure. A gear 31 meshes with the rack 30 and is mounted on a rotatable shaft 32 which may be rotated manually by means of a gear 33 mounted on the outer end of a shaft 32. A manually operable traverse wheel 36 is mounted on the outer end of a shaft 34 and is connected by a gear 35 to rotate the gear 33, the gear 31 and the rack bar 30 so that the table 11 may be traversed longitudinally when desired.

The table 11 may be reciprocated longitudinally by a power operated mechanism, such as shown in the prior patent above referred to. This mechanism may comprise a rotatable power

driven shaft 40 which is driven by means of a multiple speed drive contained within a casing 41, details of which have not been shown in the present case since they are not considered part of the present invention. For details of this mechanism, reference may be had to the above-mentioned prior patent. The rotatable shaft 40 is connected through a reversing clutch (not shown) which is actuated by means of a reverse lever 43. The reversing lever 43 is actuated by reversing dogs 44 and 45 which are adjustably mounted in a T-slot 46 on the front edge of the table 11.

In the production of automobile pistons, it is frequently necessary to grind either a portion of the piston or the entire outer surface of the piston to an oval or elliptical form. It is desirable to provide a grinding apparatus which is arranged to oscillate the work supporting spindle toward and from the grinding element so as to produce the desired oval or elliptical periphery on the piston or work piece being ground. For a production grinding machine, such an apparatus may be built into the machine as a permanent part of the grinding machine. In repair shop work, however, it is frequently necessary for the shop to be equipped with grinding apparatus suitable for grinding the various replacement parts of the automobile to accurately fit in place of the part being replaced. For example, when an automobile cylinder becomes worn or the piston becomes worn, it is necessary to replace the piston and to provide a piston which accurately fits the worn cylinder. It is, therefore, desirable that the piston grinding apparatus be provided as an attachment which may be readily applied to and utilized on a standard cylindrical grinding machine.

The improved piston grinding attachment comprises a supporting member or shaft 50 having conically shaped center holes 51 and 52 on opposite ends thereof which are arranged to be supported by a headstock center 53 and a footstock center 54. The bar 50 supports a pair of spaced brackets 56 and 57. Each of these brackets is provided with cylindrical bores which fit upon the bar. The brackets 56 and 57 are held in a fixed position on the bar 50 by means of pins 58 and 59. The upper ends of the brackets 56 and 57 are provided with bearings 60 and 61, respectively, which serve to rotatably support a work spindle 62. A work holding and centering plate 64 is mounted on one end of the spindle 62 and is provided with a shoulder 65 which is adapted to fit within the open end of a work piece, such as a piston 66. The shoulder 65 serves to center the piston 66 with relation to the axis of rotation of the spindle 62 and also serves to locate the piston endwise. The piston 66 is arranged to be clamped rigidly in position on the plate 64 by means of a clamping mechanism comprising a pin 67 passing through the holes 68 and 69 in the piston 66. The pin 67 also passes through a hole 70 in an enlarged head 71 of a clamping rod 72. The rod 72 is held against rotation by means of a key 73, fixed to the plate 64, which engages a keyway 74 in the rod 72 so that the rod is held against rotation but may slide endwise. The rod 72 passes through a central aperture 75 within the spindle 72 and has a reduced portion 76 which extends through the entire length of the spindle 62. The end of the portion 76 is provided with a screw thread 77 which is engaged by a manually operable nut 78. The work piece or piston 66 is positioned on

the shoulder 65, a pin 67 is passed through the hole 68 of the piston and through the hole 70 in the rod 72 and then through the hole 69 on the other side of the piston. After this pin 67 has been inserted in place, the manually operable knob 78 may be rotated to draw the clamping rod 72 toward the left, as viewed in Fig. 2, which serves to move the pin 67 toward the left and thereby clamp the piston 66 in rigid operating position on the plate 64.

In the grinding of pistons, such as those used in the modern automobile engine, which are in many cases made of an aluminum alloy casting, the metal expands due to temperature change. The piston expands greater on the diameter coinciding with the axis of the wrist pin and it is, therefore, desirable that at least this portion of the piston be ground to an oval or elliptical shape to compensate for the expansion thereof. In the piston grinding practice, it is also common practice to grind the entire surface of the piston to an oval or elliptical shape to compensate for the expansion of the piston due to heating to a running temperature so that when the piston becomes expanded due to normal temperature, the piston will fit the cylindrical surface of the cylinder.

In order to obtain the desired elliptical or oval shape on the piston, it is desirable to provide a suitable mechanism for rocking the piston 66 toward and from the grinding wheel 20 as the piston is rotated so as to generate the predetermined shape thereon. Such a mechanism preferably comprises a cam carried by the work supporting spindle 62 which engages a follower 35 which is fixed to part of the machine structure, such as the table, so that when the spindle is rotated to rotate the piston in operative relation with the grinding wheel, the piston will be oscillated during its rotation so that the grinding wheel will produce the desired shape on the periphery of the work piece being ground. In the preferred form, a camming member is provided which is adjustable so that the extent of oval or elliptical surface may be varied according to the particular requirements. Such a feature is highly important in the use of such an apparatus in a repair shop where automobile motors of various types are being ground so as to enable the elliptical shape produced on the piston to be varied as required. As illustrated in the drawing, a fixed follower member 80 is supported on the bar 50. The follower member 80 is fastened to a bracket 81 by screws 82 and 83 and the bracket 81 is held in fixed relation on the table 11 by screws 84 and 85, as shown in Figs. 3 and 4.

As shown in Fig. 3, the follower member is provided with an internal cylindrical surface 85. The spindle 62 carries a camming member 86 which is keyed thereon by a key 81. The camming member is provided with a cylindrical surface 88 which is arranged to ride in engagement with the cylindrical surface 85.

To maintain the camming member 86 in operative engagement with the surface 85 of the follower member 80, a spring 89 is connected at one end to a stud 90 which is fixed to the follower member 80. The other end of the spring 89 is fastened to a stud 91 which is fixed to the supporting arm 56. The spring 89 is of a sufficient tension to maintain the camming member 86 in operative engagement with the follower surface 85 during the grinding operation. When the camming member 86 is rotated, as above described, with its cylindrical surface 88 rotat-

ing in contact with the cylindrical surface 85, the spindle 62 will be held in a fixed relation with the grinding wheel and a true cylindrical surface will be ground on the periphery of the cylinder.

In order to rock the spindle 62 toward and from the operative face of the grinding wheel to grind the desired relief on opposite sides of the piston, a pair of diametrically opposed adjustable rollers 96 and 97 are mounted on studs 98 and 99, respectively, on the camming disk 86. The studs 98 and 99 are arranged in elongated slots 101 and 102 in the camming plate 86. The studs 98 and 99 may be held in adjusted position relative to the plate 86 by means of the locking nuts 104 and 105. The elongated slots are of a sufficient length so that the rollers may be adjusted toward the center of the camming plate 86 to a sufficient extent so that the peripheries of the rollers 96 and 97 do not project beyond the periphery of the camming disk 86. In such a case, when the spindle 62 is rotated the cylindrical surface 88 of the camming member 86 rides against a portion of the cylindrical surface 85 and causes no rocking motion of the spindle and, therefore, produces a cylindrical surface on the work piece or piston 66.

If it is desired to grind the piston or a portion thereof to an elliptical or oval shape, the studs 98 and 99 are adjusted so that the rollers 96 and 97 project beyond the periphery of the camming disk 86 by an amount equal to the difference between the radii of the surface it is desired to produce on the piston being ground. That is, the rollers 96 and 97 project beyond the disk 86 by an amount equal to the difference between a radius drawn through the long and the short axis of the oval or ellipse to be produced on the piston 66. When the rolls are adjusted to such a position, as indicated in Fig. 3, when the spindle is rotated the rollers 96 and 97 are brought into engagement with the follower surface 85 to rock the spindle 62 toward and from the operative face of the grinding wheel. After the camming disk 86 rotates through a partial turn, the camming disk 86 contacts with the follower surface 85 and the roller 96 moves away from the follower surface 85. During a partial turn, following this relationship of the parts, the camming disk rides on the follower surface to grind a concentric portion on the piston until the next roller 97 engages the follower surface 85 and again rocks the spindle toward and from the periphery of the grinding wheel to grind away a portion of the piston on its diametrically opposite sides. By adjusting the positions of the rollers 96 and 97 relative to the axis of the supporting spindle 62, the extent of oval or ellipse produced on the finished product may be varied. In the arrangement shown in Figs. 1 to 3 inclusive, the long axis of the oval or ellipse produced remains constant and the short axis of the ellipse is varied.

In order to rotate the spindle 62 during its oscillation in grinding a work piece, a driving mechanism is provided comprising a gear 110 mounted on the spindle 62. The gear 110 meshes with an intermediate gear 111 which in turn meshes with a gear 112 rotatably mounted on the supporting bar 50. A sleeve 113 is formed integral with the gear 112 and is provided with an outwardly extending flange 114 which is provided with an aperture 115. The aperture 115 is engaged by a driving pin 116 carried by the rotatable driving plate 117 on the headstock 18.

A modified form of camming device is illus-

trated in Fig. 4, in which the bracket 80 is provided with a fixed follower surface 120. A camming member 121 is supported on a bushing 122 which is mounted on the spindle 62 and is keyed thereto by a key 123. The camming member 121 is arranged so that its periphery may be adjusted to grind either a true cylindrical surface, an oval or elliptical surface. In order to adjust the camming ring 121, a plurality of opposed adjusting screws 124, 125, 126, and 127 are screw threaded through the ring 121 and bear against the sleeve 122. By slackening off on the adjusting screws 124 and 125 and tightening the screws 126 and 127, the ring 121 may be flexed to an oval or elliptical shape so that when rotated by the spindle 62 in contact with the fixed follower 120, it will cause a rocking movement of the spindle 62 and the work piece 66 to generate a predetermined oval or elliptical shape on the work piece. If desired, the fixed follower member 120 may be replaced with a rotatable follower roller.

The operation of this apparatus is readily apparent from the foregoing disclosure. The grinding attachment 18 is inserted in place on a cylindrical grinding machine with the bar 50 supported on the headstock center 53 and footstock center 54 and the driving pin 116 engaging the aperture 115 on the driving flange 114. The camming member 86 is then adjusted to produce a form of the desired shape, that is the camming rollers 96 and 97 are adjusted in a diametrical direction to project the desired amount from the disk 86. In the modified form, as shown in Fig. 4, the screws 124, 125, 126, and 127 are adjusted to flex the ring 121 to produce a camming surface of the desired shape. A work piece, such as a piston 66, is then mounted in position on the shoulder 65 of the driving plate 64, and the locking pin 67 is then passed through the holes 68 and 69 of the piston and through the hole 70 in the clamping member 72. The clamping nut 78 is then rotated to draw the clamping rod 70 toward the left, as viewed in Fig. 2, to lock the piston securely in operating position. The headstock motor is then started to rotate the work through the driving gear 112, the gear 111 and the gear 110 which serve to rotate the spindle 62 and at the same time oscillate the spindle to cause the piston 66 to rotate and rock toward and from the operative face of the grinding wheel which grinds a predetermined cylindrical, oval or elliptical face on the periphery of the piston.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. A grinding attachment for a grinding machine having a rotatable grinding wheel for grinding non-circular objects, comprising a pivotally mounted support, a frame on said support, a rotatable spindle on said frame, a work support on said spindle, means to rotate said spindle, means including a cam to rock said support and frame to rock the work piece toward and from the grinding wheel, and means to adjust the contour of said cam to vary the extent of rocking of said support.
2. A piston grinding attachment for a cylindri-

cal grinding machine having a rotatable grinding wheel, a head and footstock center, comprising a support arranged to be supported on said centers, a frame on said support, a rotatable spindle on said frame, a work support on said spindle, means to rotate said spindle, means including a cam to rock said support and frame to rock the work piece toward and from the grinding wheel, and means to adjust the contour of said cam to vary the extent of rocking of said support.

3. A grinding machine comprising a rotatable grinding wheel and a rotatable work support which are movable longitudinally and transversely relative to each other, means to traverse the work support and grinding wheel longitudinally relative to each other, means to feed said work support and grinding wheel transversely relative to each other, means to rotate said work support, a pivotally mounted support for said rotatable work support, means including a cam to rock said pivotally mounted support to cause the work to approach and recede from the grinding wheel to grind a non-circular shape on the work, and means to adjust the contour of the cam to vary the extent of rocking movement of the work to vary the contour produced thereon.

4. A grinding machine comprising a rotatable grinding wheel and a rotatable work support which are movable longitudinally and transversely relative to each other, means to traverse the work support and grinding wheel longitudinally relative to each other, means to feed said work support and grinding wheel transversely relative to each other, means to rotate said work support, a pivotal support for said work support, means including a cam to rock said support to cause the wheel to approach and recede from the grinding wheel to grind a non-circular shape on the work, and means including a plurality of adjustable rollers carried by said cam which may be adjusted towards or from the cam axis to vary the extent of said camming movement to vary the contour produced on the work piece.

5. A grinding machine comprising a rotatable grinding wheel and a rotatable work support which are movable longitudinally and transversely relative to each other, means to traverse the work support and grinding wheel longitudinally relative to each other, means to feed said work support and grinding wheel transversely relative to each other, means to rotate said work support, a pivotal support for said work support, means including a cam to rock said support to cause the wheel to approach and recede from the grinding wheel to grind a non-circular shape on the work, and means including a pair of adjustable diametrically opposite rollers carried by said cam which may be adjusted in a diametrical di-

rection to vary the extent of said camming movement to vary the contour produced on the work piece.

6. A grinding machine comprising a rotatable grinding wheel and a rotatable work support which are movable longitudinally and transversely relative to each other, means to traverse the work support and grinding wheel longitudinally relative to each other, means to feed said work support and grinding wheel transversely relative to each other, means to rotate said work support, means to clamp a work piece thereon, a pivotal support for said work support, and means including an adjustable cam to rock said work support to cause the work to approach and recede from the grinding wheel to grind a non-circular shape on the periphery of the work piece, and a plurality of adjusting screws to flex said cam to vary its contour so as to vary the shape produced on the periphery of said work piece.

7. A grinding machine comprising a rotatable grinding wheel and a rotatable work support which are movable longitudinally and transversely relative to each other, means to traverse the work support and grinding wheel longitudinally relative to each other, means to feed said work support and grinding wheel transversely relative to each other, means to rotate said work support, means to clamp a work piece thereon, a pivotal support for said work support, and means including an adjustable cam to rock said work support to cause the work to approach and recede from the grinding wheel to grind a non-circular shape on the periphery of the work piece, and opposed adjusting screws to flex said cam to vary its contour so as to vary the shape produced on the periphery of said work piece.

8. A cylindrical grinding machine having a rotatable grinding wheel, a transversely movable wheel slide, a feeding mechanism to move said slide transversely, a longitudinally movable table, means to traverse said table longitudinally relative to said wheel, a head and footstock on said table, and a piston grinding attachment therefor comprising a supporting member arranged to be supported by said head and footstock, a frame pivotally mounted on said support, a rotatable spindle on said frame, a work support on said spindle, means to rotate said spindle, means including a cam to rock said support and frame so as to rock the work piece toward and from the operative face of the grinding wheel, and means to adjust the contour of said cam to vary the extent of rocking movement of the support and thereby vary the contour produced on the work piece.

CLARENCE J. GREEN.
